The ornamental design for a wall mount, as shown and described.

USPC D21/662, 673, 686, 691, 694, 826;
D25/62, 66, 68, 119, 126, 136; D6/329;
D8/323, 354
CPC A63B 21/00047; A63B 21/078; A63B
21/169; A63B 71/023**DESCRIPTION**

See application file for complete search history.

FIG. 1 is a top, front, right perspective view of a wall mount showing my new design;
FIG. 2 is a front view thereof;
FIG. 3 is a top view thereof;
FIG. 4 is a bottom view thereof;
FIG. 5 is a right side view thereof; and,
FIG. 6 is a left side view thereof.(56) **References Cited**

The broken lines immediately adjacent to the shaded area define the bounds of the claimed design and form no part thereof. The broken lines depicting the remainder of the wall mount show portions that form no part of the claimed design. The broken lines showing lettering in FIGS. 1-2 show example environment that forms no part of the claimed design.
